HANGER

Wesley R. Wilhelm, Minneapolis, Minn.

Application December 21, 1944, Serial No. 569,199

2 Claims. (Cl. 248—110)

1

This invention has relation to a hanger for articles such as brooms, mops, rakes, hoes, etc.

An object of the invention is to provide a hanger of simple, inexpensive, novel and improved construction.

A further object is to provide a hanger for articles which will include several new features and characteristics of construction designed with the end in view of rendering the hanger an improvement over hangers for the same general purpose heretofore known.

And a further object is to provide a hanger constituted as hereinafter set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawing forming a part of this specification,

Fig. 1 is a perspective view of a hanger made according to the invention as when applied to use;

Fig. 2 is an enlarged front elevational view of the hanger of Fig. 1;

Fig. 3 is a top end elevational view of said hanger as it would appear from above in Fig. 2;

Fig. 4 is a sectional view, taken on line 4—4 in Fig. 3; and

Fig. 5 is a bottom end elevational view, on a reduced scale, disclosing several hangers made according to the invention as when nested.

The hanger here presented consists of a single piece of rigid material, desirably metal, bent to provide a flat body 10 of said hanger and flat wings 11, 11 integral with and set at angular relation to said flat body 10.

The flat wings 11, 11 extend forwardly from the opposite side edges 12, 12 of the flat body 10 in diverging relation to each other. The angle of the bend in the rigid material or metal of the hanger at each of the side edges 12, 12 of said flat body 10 is as disclosed substantially the same, and, in the disclosure as made, each flat wing is set at an angle of approximately ninety-eight degrees, more or less, with respect to the flat body 10.

The upper part of each flat wing 11 is cut away

2

to provide a hook portion 13 defined or bounded at its upper margin or edge by a curvilinear seat 14, of arc shape as shown, and each curvilinear or arc-shape seat 14 curves smoothly downwardly and outwardly from location adjacent the upper end of the corresponding side edge 12 of the flat body 10 to substantially the midlength of the curvilinear or arc-shape seat and thence smoothly upwardly and outwardly to a curvilinear part or surface 15 of the corresponding flat wing 11 at the upper, outer margin or edge of said flat wing.

The upper margin or edge 16 of the flat body 10, between and at elevation above the curvilinear or arc-shape seats 14, is of curvilinear configuration, of arc shape as shown, and the lower, outer portions of said upper margin or edge 16 merge smoothly into the inner upper portions of said curvilinear or arc-shape seats 14. The outer, upper portions of the curvilinear or arc-shape seats 14 merge smoothly into the inner, lower portions of the curvilinear parts or surfaces 15.

A key hole 17 disposed at the midwidth of the upper portion of the flat body 10, near the upper margin or edge 16, is for readily and easily removably receiving an attachment means, such as a screw or nail (not shown), for the hanger, and a hole 18 disposed at the midwidth of the lower portion of said flat body 10, near the lower margin or edge 19 of the flat body, is for receiving a stabilizer, such as a screw or nail (not shown), for said hanger.

In the disclosure as made, the lower margin or edge 19 of said flat body 10 is substantially straight and is in substantially perpendicular relation to the opposite side edges 12, 12 of the flat body, and the outer margins or edges 20 of the flat wings 11, 11 curve smoothly upwardly and outwardly from the locations of the outer ends of said lower margin or edge 19 to the locations of the curvilinear parts or surfaces 15, 15 respectively.

The construction and arrangement are such that when the hanger is mounted in vertical position upon a wall, or other support for the hanger, the curvilinear or arc-shape seats 14, 14 will be disposed substantially horizontally with their midlengths at lower elevation than their inner and outer end portions.

In Fig. 1 of the drawing, the hanger is disclosed as when applied to use. The head of a broom 21 is disposed in adjacent relation to the flat body 10, the opposite side portions of the broom head are rested upon the curvilinear or arc-

shape seats 14, 14 and the handle of said broom is situated between and extends downwardly from the flat wings 11.

In Fig. 5 of the drawing, several of the hangers are disclosed nested, as, for example, when to be stored or shipped.

It will be apparent that the hanger here presented readily and easily can accommodate articles, such as brooms, mops, rakes, hoes, etc., which vary considerably in size. The divergence of the flat wings 11, 11 constitutes provision for acceptance by said hanger of articles which vary considerably in width, and the configuration of the curvilinear or arc-shape seats 14, 14 constitutes provision for acceptance by the hanger of articles which vary considerably in thickness. Stated otherwise, the hanger can be employed to support articles which vary considerably in both width and thickness.

What is claimed is:

1. A hanger constituted as a single piece of rigid, flat material bent to provide a flat body and diverging, flat wings integral with opposite side edges of said flat body and set in angular relation to the body adjacent a single surface thereof, each of said flat wings including a flat hook portion defining an upwardly opening curvilinear seat constituted as an upper edge of the corresponding flat wing of said hanger, each of said curvilinear seats curving smoothly downwardly and outwardly from a location adjacent an inner part of the corresponding flat hook portion to an intermediate part of the curvilinear seat and thence smoothly upwardly and outwardly to an outer part of the corresponding flat hook por- 35

tion, and the curvilinear seats provided by said flat wings being disposed in aligned relation in a plane parallel with said flat body.

2. A hanger constituted as a single piece of rigid, flat material bent to provide a flat body and diverging, flat wings integral with substantially parallel, opposite side edges of said flat body and set in angular relation to the flat body adjacent a single surface thereof, each of said flat wings including a flat hook portion defining an upwardly opening curvilinear seat constituted as an upper edge of the corresponding flat wing of said hanger, the adjacent side edges of said flat body merging into said curvilinear seats and each of the curvilinear seats curving downwardly and outwardly from the merging location with the adjacent side edge of said flat body to an intermediate part of the curvilinear seat and thence upwardly and outwardly to an outer part of the corresponding flat hook portion, and the curvilinear seats provided by said flat wings being disposed in aligned relation in a plane parallel with said flat body.
